UNITED STATES PATENT OFFICE.

JOHN BENNETT, OF HEMPSTEAD, NEW YORK.

FOLDABLE STEP AND WALL LADDER.

1,192,734.

Specification of Letters Patent. Patented July 25, 1916.

Application filed June 23, 1915. Serial No. 35,858.

To all whom it may concern:

Be it known that I, JOHN BENNETT, a subject of the King of Great Britain, residing at Hempstead, in the county of Nassau and State of New York, have invented new and useful Improvements in Foldable Step and Wall Ladders, of which the following is a specification.

This invention relates to foldable step and wall ladders and it consists in the novel features hereinafter described and claimed.

An object of the invention is to provide a ladder of the character indicated which may be easily and quickly transformed from an extensible step ladder to an extensible wall ladder, and vice versa. The parts of the ladder are so arranged that they may be folded in compact form for storage or transportation. Also the ladder includes features which permit the same to be extended when used as a step ladder in order that the structure may be placed in position upon stair steps or upon inclined surfaces.

With the above objects in view the structure includes a step and a prop section pivotally connected together and both provided with steps or rungs. Extensible step and prop sections are mounted upon both of the first mentioned sections respectively and these extensible sections if desired may be provided with movable steps. Securing devices are provided for holding the said movable steps at adjusted position along the extensible sections.

In the accompanying drawings:—Figure 1 is a perspective view of the structure showing the same set up as a step ladder. Fig. 2 is an edge elevation of the same showing the parts set up as a wall or extension ladder. Fig. 3 is a similar view showing the parts arranged for using the ladder on a set of steps. Fig. 4 is a transverse sectional view of one of the extensions cut on the line 4—4 of Fig. 2. Fig. 5 is a sectional view of the structure cut on the line 5—5 of Fig. 4.

As illustrated in the accompanying drawing the ladder consists of sections 1 and 2, the section 1 being provided with arms 3 with which one end of the frame 2 is pivotally connected. The section 1 is provided with steps or treads 4, and the section 2 is provided with rungs 5. The steps 4 and rungs 5 are fixed to the respective sections upon which they are mounted. The section 1 is provided in the vicinity of its lower end and at its sides with guides 6 which receive

the upper end portions of a step extension section 7. The side bars of the step extension section 7 are provided with longitudinal slots 8 and studs 9 pass through the said slots and are provided at their outer ends with wing nuts 10. By loosening the nuts 10 the section 7 may be moved longitudinally along the sides of the section 1 and when the said section 7 is at a desired position with relation to the said section 1 it may be secured by tightening the nuts 10 upon the studs 9.

Treads 11 are located between the sides of the section 7 and the ends of the said treads are normally held in close contact with the inner surfaces of the side bars of the section 7. The treads 11 are provided at their under side with recesses 12 which receive tie rods 13, and parts connected therewith. The tie rods 13 are provided at one end with heads 14 which bear against the outer surface of one side-bar of the section 7 and at their other ends the said tie rods are provided with eyes 15. Screws 16 are threaded in the outer ends of the eyes 15 and pass transversely through the slot 8 of one of the sides of the section 7. The screws 16 carry at their outer ends wing heads 17, which, when the said screws are tightened in the eyes 15 are adapted to bear against the outer surface of one of the sides of the section 7, whereby the treads 11 are held at adjusted positions along the said section 7.

It is apparent that by loosening the screws 16 all of the treads 11 may be assembled or folded in close contact at the lower ends of the slots 8 and by loosening the wing nut 10 the section 7 may be adjusted along the sides of the section 1. Therefore the section 7 may be extended or folded with relation to the section 1 to any extent within the limit of the length of the slots 8 and the section 7 may be secured with relation to the section 1 at any point between the ends 100 of the said limit of movement. Also the treads 11 may be secured at desired intervals apart along the section 7.

Guides 18 are mounted in the vicinity of the free ends of the prop section 2 and at the sides thereof, and the side bars of a prop extension section 19 are slidably received in said guides 18. The side bars of the section 19 are provided with longitudinally disposed slots 20 and studs 21 are mounted upon the section 2 and are received in the said slots 20. Wing nuts 22 are threaded

upon the studs 21 and when tightened secure the section 19 at adjusted positions with relation to the section 2. If desired, the section 19 may be provided with adjustable treads similar to the treads 11 hereinbefore described in connection with the section 7 and the said treads may be secured along the section 19 by similar means provided for securing the treads 11 upon the section 7.

10 Cross bars 23 are secured at their ends to the opposite ends of the opposite sides of the section 19 and serve as means for holding the said sides in proper position with relation to each other. Clips 24 are mounted at one 15 end of the cross bars 23 and are provided with bolts 25, which pass through the slots 20 and serve as means for securing one end of the bars 23 with relation to the sides of the section 19.

20 It is apparent that by loosening the nuts 22 the section 19 may be shifted along the section 2 and secured at any desired point, when the said nuts 22 are tightened upon the studs 21. Therefore when the structure 25 is used as a step ladder the parts may be secured as shown in Fig. 3, whereby the ladder can be conveniently and safely used upon stair steps, or upon an inclined surface.

Struts 26 are pivotally connected with the 30 upper end portion of the section 1 and may be engaged with studs 27, mounted upon the section 2 whereby the said frames may be securely held in parallel relation with respect to each other as most clearly shown in 35 Fig. 2 of the drawing. When so secured the ladder may be used as an extension wall ladder.

From the foregoing description taken in conjunction with the accompanying drawings, it will be seen that a ladder of simple 40 and durable structure is provided and that

the structure may be easily and quickly transformed from a ladder of the step ladder type to a wall ladder and that the parts may be extended or folded at will to permit of the use of the structure under various conditions and circumstances and to permit the same to be folded in compact form for shipment, storage or other purposes.

Having described the invention what is claimed is:—

A ladder comprising step and prop sections pivotally connected together, guides fixedly mounted at the free end portions of the sides of said sections, studs fixedly mounted at the free end portions of the sides of said sections at points between the said guides and the point of pivotal connection between the said sections, a step extension section having its sides slidably received in the guides upon the step section, the sides of the said step extension section having longitudinally disposed slots which receive the studs upon the step section, steps 60 movably mounted between the sides of the step extension section and having securing devices which pass through the slots in the sides of the said step extension section, said securing devices being embedded in the steps 70 above the lower surfaces thereof, a prop extension section having sides slidably received in the guides upon the prop section, the sides of the prop extension section having longitudinally disposed slots which receive the studs 75 upon the said prop section.

In testimony whereof I affix my signature in presence of two witnesses.

JOHN BENNETT.
